RETAINING DEVICE

Charles H. Rollason, Wheeling, W. Va., assignor
to Wheeling Steel Corporation, Wheeling,
W. Va., a corporation of Delaware

Application April 5, 1933, Serial No. 664,511

5 Claims. (Cl. 220—61)

This invention relates broadly to retaining devices, and more particularly to devices for use in retaining covers or heads in place on containers or the like. It relates still more particularly to retaining devices for maintaining heads in place on containers such as sheet metal drums having outward peripheral projections at their mouths.

5 I preferably utilize discontinuous retaining means of the type adapted to be contracted about the container or the like to maintain the cover or head in place and to be expanded or permitted to expand so as to allow of removal of the retaining means so that the head or cover may be removed. The invention is in the nature of an improvement over prior devices of this same type whereby better and more efficient operation is obtained. Other details, objects and advantages of the invention will become apparent as the following description of a present preferred embodiment thereof proceeds.

In the accompanying drawing I have shown a present preferred embodiment of the invention, in which

Figure 1 is a fragmentary elevational view with a portion in vertical cross-section of a container having a head applied thereto and retaining means for retaining such head in place;

Figure 2 is an elevational view of the retaining device shown in Figure 1 in expanded position;

Figure 3 is a horizontal cross-sectional view through the retaining device when in contracted position as shown in Figure 1;

Figure 4 is a detail elevational view partly in cross-section of one of the operating members;

Figure 5 is a detail elevational view of another of the operating members;

Figure 6 is a vertical cross-sectional view taken on the line VI—VI of Figure 5; and

Figure 7 is a perspective view of another operating member.

Referring more particularly to the drawing, there is shown in Figure 1 a sheet metal drum 2 having an outwardly turned peripheral flange or bead 3 formed at its mouth. The drum 2 as shown is of circular cross-section and preferably has a permanently attached bottom. It may be of any preferred or well known construction.

The drum is provided with a head 4 which has a peripheral cupped portion 5 adapted to overlie and cooperate with the bead 3 of the drum in a manner well known in the art. A gasket 6 is preferably interposed between the portion 5 of the head and the bead so that a tight or sealed joint between the drum and the head may be made.

There is provided a retaining device comprising discontinuous retaining means shown as a split sheet metal ring 7 of generally U-shaped cross-section, although the specific form of the discontinuous retaining means may be varied to suit the particular conditions encountered. The ring is adapted to be somewhat expanded or enlarged in diameter to enable it to be placed about the upper portion of the drum when the head is in place thereon and then to be contracted about the portion 5 of the head and the bead 3 of the drum so as to exert a wedging action thereon, tending to force the same together so as to tightly grip the packing 6 therebetween and form a tight or sealed joint. In cross-section the ring 7 preferably has a curved intermediate portion 8 connecting two substantially straight portions 9 (Figure 1) which, upon contraction of the ring, tend to slide by wedging engagement in the radial direction to maintain the cover tightly in place on the drum.

Pivoted at 10 to one portion of the ring adjacent the split therein is a link or saddle plate 11. Pivoted at 12 to the opposite portion of the ring adjacent the split is another link 13. Pivoted to the link or saddle plate 11 at 14 and to the link 13 at 15 is a contracting member or lever 16. The saddle plate 11, link 13 and contracting member or lever 16 are adapted cooperatively to contract the ring 7, this being accomplished by grasping the upper portion of the lever (Figure 2) and turning the same in the clockwise direction until the parts assume the relationship shown in Figure 1. Such members are also so constructed and arranged that when in contracted position they will partially embrace the ring to strengthen the same at the split portion thereof and to insure maintaining of a tight closure. To this end the saddle plate 11 has a portion 17 extending horizontally above the plane of the ring and joining a generally downwardly extending portion 18, such portion 18 lying within the head so that when the parts of the ring are in contracted position such portion of the saddle plate assists in preventing accidental displacement of the parts. The lever 16 similarly has a horizontally extending portion 19 and a downwardly extending portion 20, and the link 13 has an inwardly extending portion 21.

Upon contraction of the retaining device the pivot 14 preferably moves below a line joining the pivots 10 and 12, and the pivot 15 moves approximately in line with, or slightly above, such line so that the outward reaction exerted

on the ring by the drum and head will tend to tighten the connection rather than loosen it. Connected with the ring at 22 is a lug 23 having an ear 24 provided with a hole 25 adapted, 5 when the parts are in contracted position, to be aligned with a hole 26 in the lever 16 to receive a seal or the hasp of a padlock to prevent unauthorized removal of the head from the drum.

10 The provision of the two links 11 and 13 carrying the lever 16 in such manner that the lever is not directly pivoted to the ring accomplishes two particular advantages, one being that an increased mechanical advantage in contracting 15 the ring is obtained, and another that the ends of the ring at the split portion thereof automatically tend to align themselves upon application of the retaining device.

10 While I have shown and described a present preferred embodiment of the invention, it is to be distinctly understood that the same is not limited thereto, but may be otherwise variously embodied within the scope of the following claims.

25 I claim:

1. A retaining device comprising discontinuous retaining means adapted for application to a container or the like, a lever, a link pivoted to a portion of the retaining means adjacent a discontinuity thereof and pivoted to the lever at a point remote from an extremity thereof, a second link pivoted to another portion of the retaining means adjacent said discontinuity and opposite said first mentioned portion and pivoted to the lever at a point more remote from said extremity thereof than said first mentioned point, said second mentioned link during operation of the device normally extending from said retaining means generally in a direction opposite said extremity of said lever.

40 2. A retaining device comprising discontinuous retaining means adapted for application to a container or the like, a link pivoted to a portion of the retaining means adjacent a discontinuity thereof, a second link pivoted to another

portion of the retaining means adjacent said discontinuity and opposite said first mentioned portion, and a member to which said links are respectively pivoted at spaced points, a line joining said points during operation of the device 5 normally crossing said retaining means.

3. A retaining device comprising discontinuous retaining means adapted for application to a container or the like, a link pivoted to a portion of the retaining means adjacent a discontinuity thereof, a second link pivoted to another portion of the retaining means adjacent said discontinuity and opposite said first mentioned portion, and a member to which said links are respectively pivoted at spaced points, said links 15 being so constructed and arranged that during operation of the device they normally extend generally in opposite directions from said member.

4. A retaining device comprising discontinuous 20 retaining means adapted for application to a container or the like, a link pivoted to a portion of the retaining means adjacent a discontinuity thereof, a second link pivoted to another portion of the retaining means adjacent said 25 discontinuity and opposite said first mentioned portion, and a member to which said links are respectively pivoted at spaced points, said links during operation of the device normally extending generally in opposite directions from said member, said member having means connected therewith for operating the same.

5. A retaining device comprising discontinuous retaining means adapted for application to a container or the like, a link pivoted to a portion 35 of the retaining means adjacent a discontinuity thereof, a second link pivoted to another portion of the retaining means adjacent said discontinuity and opposite said first mentioned portion, and a member to which said links are respectively 40 pivoted at spaced points, said member being so constructed and arranged that during operation of the device it normally crosses said retaining means.

CHARLES H. ROLLASON. 45
